APPARATUS FOR COMPRESSING SUBSTANCES

Filed Sept. 7, 1928

GEORGE T. JACOCKS
INVENTOR.

BY *M. J. Jacobsen*
ATTORNEY.

UNITED STATES PATENT OFFICE

GEORGE T. JACOCKS, OF BROOKLYN, NEW YORK, ASSIGNOR, BY MESNE ASSIGNMENTS,
TO HEAT TRANSFER PRODUCTS, INC., A CORPORATION OF NEW YORK

APPARATUS FOR COMPRESSING SUBSTANCES

Application filed September 7, 1928. Serial No. 304,413.

My invention pertains to a new and improved apparatus for pumping fluids, and more particularly vaporous or gaseous substances.

5 My invention is especially adaptable to refrigeration systems and it is in conjunction with such a system that I have illustrated the operation of my new device.

I will hereafter describe my invention as 10 applied to refrigerating systems, but it will be understood that this is by way of example only and that my new and improved compressor can be used in other systems and manners with equal advantages.

15 One of the great disadvantages in refrigeration systems of the compression type has been the leakage of refrigerant past the stuffing box of the compressor. This is apparent because the compressor handles the 20 refrigerant in a vaporous condition under considerable pressure.

It is, therefore, necessary to provide a 25 stuffing box that will be gas tight. This means an increase of the frictional load upon the operating motor to such an extent as to waste a large percentage of the power used.

The other alternative is to enclose the 30 motor and compressor in a hermetically sealed casing. While this arrangement eliminates the waste of energy, it introduces other complications that are not easy to overcome and renders the parts inaccessible for repair or replacement.

35 Another difficulty heretofore encountered in many refrigeration systems has been the transmission by the refrigerant gas of globules of oil into the condenser and into the evaporator, which impairs the efficiency of 40 these elements and may so fill up the system as to prevent the carrying on of the refrigeration cycle.

The above recited difficulties and the complicity of the moving parts of the ordinary 45 compressor result in a great many "service"

calls in connection with the operation of the system in which the compressor is used, all of which is expensive both to the manufacturer and to the ultimate consumer.

It is one object of my invention to provide means for pumping or compressing a 50 substance by drawing the same into a chamber and expelling it therefrom under the influence of the contraction and expansion of a fluid or other substance.

It is another object of my invention to provide an apparatus for circulating a refrigerant in a refrigeration system that will eliminate the commingling of the lubricant and refrigerant.

It is a further object of my invention to provide a compressor for the handling of 60 gaseous vapors which does not require that the stuffing box thereof be gas tight.

It is a still further object of my invention to provide a compressor for the handling of 65 gaseous substances in which a fluid is used as the piston for drawing in and compressing the gaseous substance.

It is a still further object of my invention to provide a compressor in which a fluid is 70 used to draw in and expel a gaseous substance and in which the path of circulation of the fluid is reversed without reversing the motive power for the fluid.

It is a still further object of my invention to provide a compressor for the handling of 75 gaseous substances in which the moving parts are few in number and operate continually in a bath of oil or other liquid so that "servicing" of the compressor is greatly reduced and practically eliminated.

It is a still further object of my invention to produce a compressor that is exceedingly 80 cheap to manufacture yet rugged in construction and efficient in operation for the purposes for which it is intended far beyond compressors now known to this art and intended for similar purposes.

My invention will be best understood by 85 90

reference to the following specification and also to the accompanying drawing, in which the single figure is a diagrammatical illustration of a refrigeration system embodying my new compressor.

5 There is diagrammatically illustrated a condenser 1, an evaporator 2, and an expansion valve 3, located between the condenser and the evaporator in the pipe 4, that connects these two elements. No further illustration 10 or description of these elements is necessary because any well-known construction of evaporator, condenser and expansion valve may be used in a refrigeration system embodying my improved compressor.

15 The condenser 1, is connected to the discharge ports 5 and 6, of my improved compressor 7. The evaporator is connected to the suction ports 8 and 9, of the compressor 7.

20 The ports 5 and 8, 6 and 9, are respectively located in cylinders 11 and 12, that are in turn located on opposite sides of the block 13. It will be noted that the ends of 25 the block 13, have reduced or shouldered portions that are screw-threaded and are adapted to engage with screw-threaded ends of the cylinders 11 and 12 to maintain the same in fluid tight connection with the valve structure. It will be apparent that many 30 other arrangements of chambers or cylinders 11 and 12 and valve structure 13 could be effected, and my invention is not limited to the arrangement shown in the drawings.

35 Each of the discharge valves 5 and 6, includes a valve chest 14, in which may be mounted any of the ordinary and usual valves, here shown as poppet valve 15, and a retaining spring 16. Each of the suction or 40 inlet ports 8 and 9, may likewise be closed by any ordinary valve 17, and retained by a spring 18.

The block 13 is provided with four vertical passages 21, 22, 23 and 24. These 45 passages do not extend entirely through the block but are connected at their lower ends by horizontally extending passages 25 and 26. The passage 25 connects the passages 21 and 22, and the passage 26 connects the 50 passages 23 and 24.

Extending horizontally through the block 13 and intersecting the passages 21 and 24, inclusive, is a valve bar 27. The bar 27 has two ports 28 and 29, adapted to respectively cooperate with the passages 21 and 22, and 23 and 24.

The bar 27, extends outwardly beyond the block 13, at each end thereof, and is there provided with outwardly projecting pins 30 and 31. The pins 30 are adapted to engage the block 13 and thus act as stops to limit the movement of the bar 27. The pins 31 are respectively engaged by a dog 32 of a ball float 35. The dog is pivoted at 33, on 60 the lug 34, that projects from the block 13.

At their upper ends the passages 22 and 23, connect with a pipe 36, that communicates with the suction side of a pump 37, that is driven by a motor 38. Any form of pump or motor may be used but in the present form of my apparatus I am using a centrifugal pump driven by an electric motor. At their upper ends the passages 21 and 24 are connected to a pipe 39, which communicates with the discharge port of 75 the pump 37.

In the operation of my improved compressor in a refrigeration system, the chamber formed by the cylinder 11, is charged with oil or any other substances that it may 80 be desired to use. It is advisable and I intend to use a fluid that does not readily mix with the particular gaseous substance being used in the system to which my compressor is connected. To further this keeping apart of the substances, I may introduce the fluid behind a flexible diaphragm with the gaseous substance on the other side of the diaphragm.

Also, when ready for operation, the condenser and evaporator and connected parts of the refrigeration system are charged with refrigerant. With this arrangement, the float 35, in chamber 11, is raised to its upper position and the float 35 in chamber 12 is in its lower position. In this position, the valve bar 27, is located with the ports 28 and 29, respectively in communication with passages 21 and 23 in which position it is retained by the engagement of the pin 31, with the dog 32, that is located in the chamber 12. It will be noted that in this position the valve bar 27, has the passages 22 and 24 closed.

When the motor 38 and pump 37 are started in operation oil will then be drawn from the chamber 11, through horizontal passage 26, vertical passage 23 and pipe 36, to the suction side of the pump 37. It will be discharged from the pump through the pipe 39, vertical passage 21, and horizontal passage 25, into the chamber 12. This operation will create a partial vacuum or a reduced pressure in the chamber 11, to thus withdraw gaseous refrigerant from the evaporator 2, into the chamber 11, and to draw condensed refrigerant from the condenser 1, into the evaporator 2. By such action the valve of the discharge port 5, will be closed and the valve of the inlet port 8, will be opened. The reverse occurs in the chamber 12 where the inlet valve 17, will be closed and the outlet valve 16 will be opened.

The filling up of the chamber 12 by the 125 fluid will put the refrigerant vapor therein under pressure and, as the chamber fills up, the pressure therein will increase. Also, as the chamber 12 fills up the level of the liquid in chamber 12 is rising and the level 130

of the liquid in the chamber 11, is lowering. When the chamber 12 becomes completely filled, or substantially so, the end of the dog 32, (in the chamber 12) rises past the 5 pin 31, and the pressure in that chamber on the end of the valve bar 27, forces that bar quickly from the position shown in the drawing to a position where the pin 31, (in the chamber 11) will move past the end of the cooperating dog 32, and thus lock the valve bar 27 in its reverse position. In this 10 reverse position, the port 28, will communicate with the passage 22 and the port 29, will communicate with the passage 24. Thus, without reversing the direction 15 of rotation of the pump 37, the suction pipe 36, is connected to the chamber 12, through the passage 22, and the discharge pipe 39 is connected to the chamber 11 through the passage 24. This will remove 20 the oil from the chamber 12, to evacuate the same and discharge it into the chamber 11. The discharge of the gaseous refrigerant into the condenser 1, and the extraction 25 of the gaseous refrigerant from the evaporator 2, is repeated and this cycle of the compressor is repeated throughout the operation of the system, which may be under 30 the control of a thermostat or any of the other well-known controls for refrigerating systems.

I have above referred to a pressure in one chamber and a partial vacuum in the other chamber. This need not necessarily be the case as in handling some refrigerants, there will merely be a difference in pressure between the two chambers but the principle of operation of my compressor will be the same. Likewise reference has been made to the 35 handling of refrigerants in gaseous form. This need not be the case as the compressor will work equally well handling the refrigerant in liquid or vaporous condition.

From the foregoing description it will be noted that I provide an apparatus for circulating the refrigerant in a system of the compression type wherein the lubricant and refrigerant are not commingled. It will be further noted that I provide a pump that 45 does not at any time handle the refrigerant vapors. Therefore, the refrigerant can not leak through the stuffing box of the pump. It is a comparatively simple matter to construct a stuffing box that is liquid tight without increasing materially the power loss in 50 overcoming frictional resistance, but as explained above it is much more difficult to make a stuffing box gas tight.

It will be further noted that I provide a 55 compressor that is continually handling lubricant throughout its cycle of operation and, therefore, no problem rises in connection with lubrication of my improved compressor.

60 It will be further noted that should any

lubricant leak past the stuffing box of the pump 37, it will only result in a very slight variation in the volumetric capacity of my compressor, and will not result in the impairment of the operation of the refrigerating system. 70

Modifications may be made in the arrangement and location of parts within the spirit and scope of my invention but such modifications are intended to be covered by 75 the appended claims.

I claim:

1. In a compressor adapted to compress fluid by the alternate exchange of a compressor fluid from one chamber to another, the combination of pumping means having intake and discharge ports; two chambers each having means for the inlet and outlet of a fluid to be compressed; valve means having a compartment for a slide valve in communication with each of the chambers; a passageway leading from each of the chambers through the valve compartment to the intake port of the pumping means; a passageway leading from each of the chambers through the valve compartment to the discharge port of the pumping means; a slide valve in the valve compartment adapted to control the flow of fluid through the passageways; and float operated means in one of the chambers for locking the slide valve against movement until the compressor fluid in such chamber reaches a predetermined volume. 95

2. In a compressor adapted to compress a fluid by the alternate exchange of a compressor liquid from one chamber to another, the combination of a pump having an inlet and an outlet; a first chamber and a second chamber each having inlet and outlet means for a fluid to be compressed; a valve body having an opening for a slide valve, communicating with each of the chambers; a first passageway leading from the first chamber through the opening in the valve body to the inlet of the pump; a second passageway leading from the first chamber through the opening in the valve body to the outlet of the pump; a third passageway leading from the second chamber through the opening in the valve body to the inlet of the pump; a fourth passageway leading from the second chamber through the opening in the valve body to the outlet of the pump; a slide valve in the opening in the valve body adapted to be moved by the pressure of the fluid to be compressed in the first chamber to a first position closing the second and third passageways and opening the first and fourth passageways, and by the pressure of the fluid to be compressed in the second chamber to a second position closing the first and fourth passageways and opening the second and third passageways; and means in the first chamber comprising 130

a float, and adapted to coact with the slide valve to lock the same against movement until the compressor fluid in that chamber reaches a predetermined volume and to release the slide valve when said predetermined volume is reached; and means in the second chamber comprising a float, and adapted to coact with the slide valve to lock the same against movement until the compressor fluid in that chamber reaches a predetermined volume, and to release the slide valve when said predetermined volume is reached.

In testimony whereof I affix my signature.

GEORGE T. JACOCKS.
